ATTORNEY.

UNITED STATES PATENT OFFICE.

KASIMIR W. NAJDER, OF ROYAL OAK, MICHIGAN, ASSIGNEE OF ONE-FOURTH TO
ISAAC S. GELLETT, OF DETROIT, MICHIGAN.

SLEEVE-VALVE ENGINE.

Application filed October 18, 1926. Serial No. 142,452.

This invention relates to internal combustion engines of the general character shown and described in my Patent No. 1,589,983, dated June 22, 1926, and its object is to provide single-sleeve-valve engines with sufficient intake and exhaust ports and with proper compression spaces so that such engines can operate at high speeds.

While the engine shown in said patent is of value in the arts, I have found that under many conditions, the area of the interior of the skirting of the cylinder head is insufficient to permit of sufficient port areas, and the present invention therefore consists in providing a compression chamber of sufficient diameter to permit proper intake and exhaust ports to be cut therein. This invention is illustrated in the accompanying drawing, wherein—

Fig. 1 is a central longitudinal section of an engine cylinder embodying the present invention;

Fig. 2 is a plan of the engine with the cylinder head removed; and

Fig. 3 is a section of the cylinder head flange.

Similar reference characters refer to like parts throughout the several views.

The cylinder 1 shown in the drawing is of well known form and the piston is designed to travel up to the plane of the outer or upper surface of the flange 2 at the outer end of the cylinder. A cylindrical drum 3 is attached to this flange and may be concentric with or eccentric to the cylinder to any extent, depending on the character of the engine construction. This drum is formed with segmental passages 4 and 5 in its wall, one for the fuel vapor and the other for the exhaust gases, and the ordinary passages 6 and 7 connect thereto.

A cylinder head 9 has a flange 11 secured to the outer end of the drum 3, and has a skirting 12 extending down into the drum, this skirting being provided with a shallow cylindrical groove 13 to receive the sleeve valve 14. The skirting 12 is formed with ports 16 and the sleeve valve is provided with corresponding ports, but the details of these ports are so fully described in said patent that those skilled in the art can properly design the valve, the ports in the skirting and the passages 4 and 5. The longitudinal length of the groove 13 will depend upon the necessary length of the valve and its travel

will depend upon the longitudinal dimensions of the ports.

Instead of the valve having an extension projecting out through the head, the present drawing shows a segmental slot 18 in the flange 2 on the cylinder 1, and the segmental extension 19 of the valve projecting through this slot, the operating mechanism for the valve being the same as that described in said patent, consisting of a shaft 21 rotating at one-half the speed of the crank shaft, the inclined crank pin 22, the connecting rod 23 with the ball 24 at the end thereof, and the socket 25 attached to the extension 19 of the valve. The upper end of the shaft 21 may be mounted in a bearing 26 attached to the flange 2.

In this engine construction, as in that of said patent, the sleeve valve is movable between stationary walls and may therefore travel its triangular path. If the compression chamber is found to be too large for certain types of fuel, the head 9 may be depressed, as indicated in dotted lines, to reduce the volume of this compression chamber. I prefer to mount the spark plug in a threaded hole 31 in the center of this head.

As it may at times be desirable to vary the time of opening and closing the ports, I prefer to elongate the holes 32 in the flange 11 for the bolts 33, as shown in Fig. 3, to permit the cylinder skirting to be shifted circumferentially relative to the valve.

The piston 34 will travel up to the plane between the cylinder 1 and chamber 3 in the usual manner and at any desired speed, the ports 16 being of sufficient size and number to permit ready escape of the exhaust gases and the free entrance of the fuel.

The details of construction and the proportions of the parts of this engine construction may all be varied by those skilled in the art without departing from the spirit of my invention as set forth in the following claims.

I claim:—

1. In an internal combustion engine, the combination of a cylinder having a radial flange at one end formed with a segmental slot, a compression chamber attached to said flange and being of greater diameter than said cylinder, a cylindrical sleeve-valve slidable in said chamber and having an extension projecting through said slot, and a head for said chamber.

2. In an internal combustion engine, the

combination of a cylinder having a radial flange at one end formed with a segmental slot, a compression chamber attached to said flange and being of greater diameter than said cylinder, a cylindrical sleeve-valve slideable in said chamber and having an extension projecting through said slot, and a head for said chamber having a skirting extending within said valve and formed with a cylindrical groove to receive said valve.

3. In an internal combustion engine, the combination of a cylinder and a cylindrical compression chamber connected thereto of greater diameter than the cylinder and having an inner end wall projecting laterally beyond the wall of the cylinder formed with a segmental slot, a cylindrical sleeve-valve slideable in said chamber, and an outer head for said chamber, and means extending from said valve through said slot whereby the valve may be actuated.

4. In an internal combustion engine, the combination of a cylinder and a cylindrical compression chamber connected thereto with its axis parallel to but spaced apart from the axis of the cylinder, a substantially radial inner end wall extending from the cylinder wall to close the overhanging portion of said cylinder and formed with a segmental slot, a head

30 for the outer end of said chamber, a cylindrical sleeve-valve slideable in said chamber

and having an extension projecting through said slot, and means to actuate the valve.

5. In an internal combustion engine, the combination of a cylinder and a cylindrical compression chamber connected thereto with its axis parallel to but spaced apart from the axis of the cylinder, a substantially radial inner end wall extending from the cylinder wall to close the overhanging portion of said cylinder and formed with a segmental slot, a head 40 for the outer end of said chamber, a cylindrical sleeve-valve slideable in said chamber and having an extension projecting through said slot, and means to actuate the valve, said 45 outer head being formed with a skirting extending through said sleeve valve and engaging said inner end wall to prevent leakage at said slot.

6. In an internal combustion engine, the combination of a cylinder, a cylindrical compression chamber of greater diameter than the cylinder connected thereto with its axis parallel to but spaced apart from the axis of the cylinder, a flange extending from the 55 cylinder to close the overhang of the compression chamber, an outer head for said compression chamber, a cylindrical sleeve-valve in said compression chamber, and means to actuate said valve.

KASIMIR W. NAJDER.
